POWDER CONTAINER

Joseph F. Rioux, Attleboro, Mass.

Application June 19, 1935, Serial No. 27,328

11 Claims. (Cl. 132—82)

This invention relates to a portable powder container frequently referred to as a powder pouch, which may be carried about by the user; and has for one of its objects the improvement in appearance of devices of this character.

Another object of the invention is the provision of a powder pouch which will have a greater extent of surface in the metal body portion thereof to be afforded ornamentation.

10 Another object of the invention is the provision of a powder pouch, the flexible portion of which will remain symmetrical with reference to the more rigid portion or body and cover thereof so that when the same is placed upon a horizontal 15 surface the parts will be disposed symmetrically rather than haphazard and out of line, such as occurs in the powder pouches which are at present on the market.

Another object of the invention is the provision 20 of a lining member for the pouch portion of the device, which may be detachably secured to the body so that the same may be readily interchanged and more easily assembled in the manufacture of the device.

25 Another object of the invention is the novel manner of securing the flexible portion of the device to the rigid portion, to eliminate the necessity of providing a separate piece for attaching the parts together and to provide a stronger and 30 better connection of the parts which go to make up the device.

With these and other objects in view, the invention consists of certain novel features of construction, as will be more fully described, and 35 particularly pointed out in the appended claims.

In the accompanying drawing:

Fig. 1 is a perspective view looking into the powder container with the cover raised.

Fig. 2 is a top plan view of the removable insert;

Fig. 3 is a section on line 3—3 of Fig. 2;

Fig. 4 is a section on line 4—4 of Fig. 1, looking in the direction of the arrow;

Fig. 5 is an elevation of the container in closed 45 position, shown as resting on a flat surface with its flexible portion symmetrically arranged with reference to its more rigid portion;

Fig. 6 is a fragmental portion of the body band or rim;

Fig. 7 is a view of the outer surface of the body or rim with a portion of mesh secured in the apertures thereof;

Fig. 8 is a sectional view of a modified form of 50 insert for use with a modified form of body;

Fig. 9 is a perspective view of a resilient ring which is used for shaping the pouch.

The usual form of powder pouch consists of a mesh bag with a separate ring and a lining inside of it, both being secured together about their 5 entering edges by a separate rim which is rolled about the two to hold them together, this lining and mesh can be pulled one from the other out of this rolled rim and when the device is laid down it is floppy in appearance and rather haphazard 10 having no symmetrical formation. I propose to improve the appearance of this construction by providing a wide band for the body which may be suitably embellished for ornamentation and to which the mesh is directly attached; and I 15 provide a removable lining which will be of a character to shape the mesh and be assisted by a metallic spring ring held within the body to so shape the flexible mesh or pouch portion by either the insert alone or by a reinforced portion of the 20 insert so that the mesh will lie flat and remain symmetrical at all times with reference to its body portion, altho being flexible and pliable as before.

Also, as an optional form I may detachably 25 mount the mesh and lining in the body so that there may be an interchangement of the flexible portion of the body and instead of using mesh I may use some sort of a silk, or leather, or fabricated leather covering which may be of a color 30 to match up with or be in accord with the ornamental theme of the dress or garment which the user may wear. A different insert may be placed into the body to match up with different dresses or garments so that the color scheme will always 35 be in harmony even with different dresses; and the following is a more detailed description of the present embodiment of this invention illustrating the preferred means by which these 40 advantageous results may be accomplished:—

With reference to the drawing, 10 designates the body band which consists of a piece of sheet stock rolled to provide the desired protruding portion 11 ornamented or suitably embellished as illustrated at 12. This body band has a cover 45 13 hinged to it at 14, which carries a mirror 15 and is suitably held in closed position by means of a catch 16 and latch 17 resiliently mounted in the body and operable by a fingerpiece 18.

The lower portion of the body band is deflected 50 inwardly as at 20 and this inwardly deflected portion is provided with a series of holes or apertures 21 to which a flexible or pliable pouch is attached consisting of an outer mesh portion 22 secured to the body by means of a helical wire 55

23 passing thru these apertures and of a construction which permits it to be flexible in all directions and suspended from the lower portion of the band.

5 The pouch also has a separable insert which is designated generally 24 in Fig. 3, and consists of leather 25, fabric or other suitable material which will prevent the powder from passing therethru, which is bound at its entrance or 10 edge 26 by a metal band 27 rolled over the opposite surfaces of the edges of the material and disposed generally in U-shape. This rim is of metal and is generally of resilient material and of a size to frictionally fit the body bend 10 and 15 be supported by the inturned or deflected portion 21 at the lower edge of the rim band. This insert consists of leather or other material which is of a sufficient stability so that it will of itself tend to force the mesh outwardly into a 20 bulge or roll 28 beyond the rim band, as shown in Fig. 4, so as to provide a generally flat under surface for the pouch and to symmetrically arrange the pouch with reference to the body, such as is disclosed in Fig. 5. However, it is frequently 25 desirable to reenforce this lining and better provide a flattening thereof and I have provided a spring ring 29 which is inserted within the lining and which tends to force the same outwardly which accentuates the generally flat surface and 30 takes up any slack and also serves to symmetrically arrange the pouch portion with reference to the relatively stiff metal band or body rim.

35 While I have illustrated in the figures described the mesh as permanently secured to the body band, in some cases I may wish to omit the mesh as permanently secured and also omit the apertures 21, and in such case the entire pouch will be removable.

40 In Fig. 8, I have disclosed an insert consisting of a lining 30 and an outer skin or covering 31 which may be of mesh, silk, fabric or any suitable material, and in this modification the insert or pouch as a whole, is removably attached 45 to the body 10 by merely forcing the rim 27 of the same into position thru the top opening thereof, the same then coming to rest upon the inturned or deflected portion 20 of the body rim and in this construction should I choose to use 50 a colored silk for the outer covering 31 I may supply with each of the units different separable inserts of differently colored outer silk or leather, or fabricated leather coverings to match the garment so that the user may snap into position 55 any selected insert which may harmonize with the garment or dress which the user is wearing or, of course, differently colored meshes could be used for the outer covering and separably applied to the rim if desired. In this modified form 60 as previously, the metal ring 29 altho not necessarily, is preferably used.

The foregoing description is directed solely towards the construction illustrated, but I desire 65 it to be understood that I reserve the privilege of resorting to all the mechanical changes to which the device is susceptible, the invention being defined and limited only by the terms of the appended claims.

70 I claim:

1. In a powder pouch, a body member having a band rim of flat sheet stock, a cover therefor, a pouch member formed of flexible material and provided with a rim, said rim being of a size to 75 fit within and contact with said body rim and

be frictionally but removably held by contact with the same.

2. In a powder pouch, a body member having a band rim, apertures in said rim, a flexible material permanently secured to said apertures, and a removable insert within said body and flexible material and frictionally held by contact with said band rim. 5

3. In a powder pouch, a body member having a band rim, apertures in said rim, a flexible material permanently secured to said apertures, a removable insert within said body and flexible material, and a rim at the open edge of the insert rigidly frictionally contacting said outer band rim. 10

4. In a powder pouch, a body member having a band rim formed of generally flat stock with its edges brought together and at least a portion of one of its surfaces generally parallel to its axis, apertures in said rim, a flexible mesh material 20 permanently secured to said apertures, and a removable powder holding pouch within said mesh material and closely following the same throughout its extent.

5. In a powder pouch, a body member having a band rim with an inwardly extending lower portion, apertures in said lower portion, a flexible mesh material permanently secured to said apertures, a removable powder holding pouch within said mesh material, and a rim provided at the 30 open edge of said pouch tightly, partially fitting said body band rim and resting on said inwardly-extending portion.

6. In a powder container, a body member of relatively rigid material, a cover therefor, a pouch 35 of material flexible in all directions secured to said body and suspended therefrom, and means for disposing the material of said pouch generally in a single plane to afford a bottom to rest upon a flat surface and to at the same time maintain 40 itself symmetrically with reference to the body member.

7. In a powder container, a body member of relatively rigid material, a cover therefor, a pouch 45 of material flexible in all directions secured to said body and suspended therefrom, and means for bulging the material of said pouch outwardly beneath the said body to assume a diameter larger than the body.

8. In a powder container, a body member of 50 relatively rigid material, a cover therefor, a pouch of mesh material flexible in all directions secured to said body and suspended therefrom, and means within said flexible material for flattening the under surface for the support of the container. 55

9. In a powder container, a body member of relatively rigid material, a cover therefor, a pouch of mesh material flexible in all directions secured to said body and suspended therefrom, and a resilient element within said flexible material for 60 disposing the material of said pouch generally in a single plane to afford a bottom to rest upon a flat surface and to at the same time maintain itself symmetrical with reference to the body member.

10. In a powder container, a body member of relatively rigid material, a cover therefor, a pouch of mesh material flexible in all directions secured to said body and suspended therefrom, and a resilient wire element within said flexible 70 material for disposing the material of said pouch generally in a single plane to afford a bottom to rest upon a flat support and to at the same time maintain itself symmetrical with reference to the body member. 75

11. In a powder container, a body member of relatively rigid material, a cover therefor, a pouch of mesh material flexible in all directions secured to said body and suspended therefrom, 5 a lining within said flexible material capable of being shaped to impart its shape to the flexible material, and a resilient element within said flexi-

ble lining material for disposing the material of said pouch generally in a single plane to afford a bottom to rest upon a flat surface and at the same time to maintain itself symmetrical with reference to the body member. 5

JOSEPH F. RIOUX.
